John L. McDowell
BY *J. H. Gibbs*
ATTORNEY

UNITED STATES PATENT OFFICE.

WARREN V. JOHNSON, OF BLOOMSBURG, AND JOHN L. McDOWELL, OF LIGHT STREET, PENNSYLVANIA, ASSIGNORS TO AMERICAN CAR AND FOUNDRY COMPANY, OF NEW YORK, N. Y., A CORPORATION OF NEW JERSEY.

MINE-CAR STRUCTURE.

Application filed April 9, 1926. Serial No. 100,869.

In the drawings:

Figure 1 is a sectional elevational view of a mine car wheel, axle and journal box constructed in accordance with our invention;

5 Fig. 2 is an end view of the structure shown in Fig. 1, and

Fig. 3 is an end view of the wheel shown in Fig. 1.

One object of the invention is to provide 10 a mine car that shall have the bearing surfaces of the wheels which take the end thrust, formed within the wheel hubs so as to be conveniently supplied with lubricating material.

15 Another object of the invention is to provide a mine car wheel with a lubricating chamber formed in the hub and connected to the axle opening and with an end thrust bearing surface in the form of an annulus 20 formed within the axle opening.

In a mine car wheel constructed in accordance with our invention a bearing surface in the shape of an annulus is formed on the hub within the axle opening for engaging 25 an end portion of a journal box. The positioning of the thrust bearing surface within the wheel hub insures lubricating material for such surface.

Referring to the drawings, an axle 1 of a 30 mine car is shown projecting through the hub 2 of a wheel 3 into an outside journal box 4. A sill 5 of a mine car is shown mounted in position on the top portion 6 of the journal box.

35 A recess 7 is shown formed in one end of the hub 2 to provide a shoulder 8 as shown in Fig. 1 of the drawing. The shoulder 8 is adapted to engage a collar 9 which is located in the recess and which is fixedly mounted in any suitable manner on the axle

1. Preferably the collar 9 engages a shoulder 10 formed on the axle. The engaging surface of the shoulder 8 with the collar 9 is preferably tapered as shown in the drawing in order to insure the supplying of lubricating material to the bearing surfaces. A second shoulder 11 in the shape of an annulus, is formed within the axle opening 45 near the opposite end of the hub. Such shoulder 11 is adapted to engage an end portion of the journal box to take up end thrust. A lubricating chamber 12, which

50 is formed in the hub 2 between the shoulders 8 and 11, is connected to the axle opening by means of a spiral groove 13. The lubricating chamber is also connected to the end of the hub by passageways 14 which extend through the shoulder 11. Such passageways are tapered or inclined as shown in Fig. 1 in order to permit the collecting of lubricating material in the chamber 12.

8 and 11, is connected to the axle opening by means of a spiral groove 13. The lubricating chamber is also connected to the end of the hub by passageways 14 which extend through the shoulder 11. Such passageways are tapered or inclined as shown in Fig. 1 in order to permit the collecting of lubricating material in the chamber 12.

The bottom portion of the journal box 4 is provided with a lubricating cellar 15 and a portion 16 which projects into the axle opening of the hub 2 to engage the shoulder 11. The portion 16, which projects into the axle opening, serves also as a dust guard

in the same manner as the collar 9 which engages the shoulder 8 at the opposite end of the hub. An opening 17 is provided in the end of the journal box for supplying lubricating material. The top portion 6 of the journal box is provided with an upwardly extending flange 18 which is fitted to the sill 5 and a downwardly extending flange 19 which is adapted to engage the journal box. Suitable bolt holes 22 are provided in the top portion 6 of the box for receiving bolts (not shown) to secure the journal box to the sill. Walls 20 project downwardly and inwardly from the top portion of the journal box to provide a guideway for securing and holding the lower portion of the box in position. In Fig. 2 of the drawing, the lower portion of the box is shown provided with projecting lugs 21 which fit within the guideway formed by the walls 20. The flange 19 limits the movement of the lower portion of the box in the guideway formed by the walls 20.

90 In a mine car wheel formed as above set forth it will be noted the bearing surface which takes the side thrust is positioned within the axle opening of the hub. Moreover, such bearing surface is directly connected to the lubricating chamber 12 within the wheel hub and to the cellar in the journal box. Consequently, such bearing surface may be conveniently supplied with lubricating material. In service the inner 100 end of the portion 16 of the journal box and the surface 11 of the wheel are in frictional contact and can be thoroughly lubricated. Thus, the inner face of the flange 18 of the journal box is held free from contact with the wheel. Prior to the present invention

the end of the journal box engaged the end of the wheel hub and as these parts commonly ran dry or free from lubricant undue wear resulted. Although our invention is illustrated by means of an outside journal box of the sliding type, it is to be understood that other types of journal boxes, such as the so-called hinge type or the so-called pedestal type may be used if so desired.

10. What is claimed is:

1. In combination, a car wheel having a hub with an axle opening therein and adapted to be rotatably mounted on an axle, and an end thrust bearing surface in the form of an annulus formed within the hub and adapted to engage a bearing box.

2. In combination, a car wheel having a hub with an axle opening therein, an end thrust bearing surface in the form of an annulus formed within the hub and adapted to engage the end of a bearing box, and a lubricating chamber within the wheel hub connected to the axle opening and to said bearing surface.

25. 3. In combination, a car wheel having a hub with an axle opening therein, an end thrust bearing surface in the form of an annulus formed within the hub for engaging a bearing box, a lubricating chamber formed within the hub and connected to the axle opening by a groove, and passageways for connecting said lubricating chamber through said annulus to the bearing box.

4. In combination, a car wheel having a hub with an axle opening therein, an annular recess formed in one end of the hub around the axle opening for receiving a collar mounted on the axle, an end thrust bearing surface in the form of an annulus formed within the hub at the opposite end thereof for engaging a bearing box, a lubricating chamber formed within the hub and connected to the axle opening by a spiral groove, and passageways for connecting said lubricating chamber through said annulus to the bearing box.

5. In combination, a car wheel having a hub with an axle opening therethrough, and a shoulder formed on the hub within the axle opening for engaging an outside journal box.

6. In combination, a car wheel having a hub with an axle opening therethrough, a shoulder formed on the hub within the axle opening adjacent each end thereof, a lubricating chamber formed in said hub and connected to said axle opening, and passageways extending from the lubricating chamber to a bearing surface on one of said shoulders.

7. In combination, a car wheel having a hub with an axle opening therein, a shoulder formed on said hub within the axle opening, a lubricating chamber formed within the hub and connected to the axle opening, and passageways extending from the lubricating chamber to the outside bearing surface on said shoulder.

8. In combination, a car wheel having a hub with an axle opening therethrough, a shoulder formed on the hub within the axle opening for engaging an outside journal box, a lubricating chamber formed in the hub and connected to axle opening, and passageways connecting the lubricating chamber to the bearing surface on said shoulder engaging the journal box.

9. In combination, a car wheel having a hub with an axle opening therethrough, a shoulder formed on the hub within the axle opening, and an outside journal box having a portion thereof projecting into said hub and engaging said shoulder.

10. In combination, a car wheel having a hub with an axle opening therethrough, a shoulder formed on the hub within the axle opening adjacent each end thereof, an axle projecting through the wheel hub and having a collar thereon adapted to engage one of the shoulders within the axle opening, and an outside journal box having a portion thereof projecting into said hub to engage the other shoulder formed within the axle opening.

11. In combination, a car wheel having a hub with an axle opening therethrough, a shoulder formed on the hub within the axle opening adjacent each end thereof, a lubricating chamber formed within the hub and connected to the axle opening, an axle projecting through the wheel hub and having a collar thereon adapted to engage one of the shoulders within the axle opening and an outside journal box having a portion thereof projecting into said hub to engage the other shoulder formed within the axle opening.

12. In combination, a car wheel having a hub with an axle opening therethrough, a shoulder formed on the hub within the axle opening, and a journal box adapted to engage said shoulder and to supply lubricant from the cellar therein.

In witness whereof we have hereunto signed.

WARREN V. JOHNSON.
JOHN L. McDOWELL.
